UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

KNITTING-MACHINE.

1,143,552.

Specification of Letters Patent. Patented June 15, 1915.

Application filed March 28, 1912. Serial No. 686,762.

To all whom it may concern:

Be it known that I, EDISON E. RANDALL, a citizen of the United States, and resident of Kankakee, county of Kankakee, State of Illinois, have invented an Improvement in Knitting-Machines, of which the following description, in connection with the accompanying drawing, is a specification, like characters on the drawing representing like parts.

This invention is particularly designed for an automatic knitting machine in which the complete article, such as a stocking, is knitted from one end to the other entirely automatically, and in which the successive stockings are united to form one continuous web.

The present invention is particularly concerned with mechanism for securing the requisite tension on the fabric for casting off the stitches from the needles in action at all times, whatever may be the character of work being performed upon the machine or whatever change may be made from one to another kind of work during the knitting operation.

The invention is particularly designed for use in connection with the fabric in which the knitting is changed from ribbed to plain work. When this change takes place one set of needles is thrown out of action, and if an improper amount of tension is placed upon the knitted web, the fabric will unravel and seriously injure, if not destroy, the value of the knitted article.

The invention is particularly designed for use in an automatic knitting machine for knitting stockings of the type shown in the reissue patent to Huse and Huse, No. 12,917, granted February 9, 1909, in which the work performed is the knitting of stockings, and in its more elaborate form the machine is designed for the knitting in one continuous web of a series of stockings automatically and completely. In this machine the usual two sets of needles, such as the dial and cylinder needles, are employed and the machine is arranged to knit as required either ribbed, plain circular or reciprocating work. In this particular form of machine the knitting begins at the toe end of the stocking, and when a woman's ribbed leg stocking is to be knitted the operation is as follows. The cylinder needles knit a short section in complete circular courses to connect with the

previous stocking; the machine then begins reciprocating knitting narrowing and widening to produce the toe pouch; upon the completion of the toe pouch the machine again knits in complete circular courses to form the foot portion; next reciprocating knitting and widening is performed to knit the heel pouch; on completion of the heel pouch the plain circular knitting is resumed to constitute the ankle portion if a plain ankle portion as usual is desired; then the second set of needles, as the dial needles, are thrown into action and the machine proceeds with the knitting of the ribbed leg to the required length. Upon the completion of the ribbed leg the dial needles are thrown out of action and a web of plain circular knitting is formed which may be used in the finish of the stocking, but which in any event constitutes the connection to the next succeeding stocking. The operation then proceeds as before continuously. If sufficient pull be given the web beneath the line where the dial needles drop out of action the fabric will be unraveled.

More specifically considered the invention comprises mechanism for taking up the knitted web including a main take-up and an auxiliary take-up or grab automatically controlled to effect the desired results.

In its preferred form this mechanism is so arranged and constructed that the web is seized by the main take-up above the point at which the ribbed knitting is completed and the auxiliary take-up seizes the web as close as possible to the point at which the stitches are being formed. Both devices are therefore arranged to reach well up within the needle cylinder. These and other features of the invention will appear more fully from the accompanying description and claims, and will be particularly pointed out in the appended claims.

The drawings illustrate only so much of a knitting machine as is necessary to a disclosure and an understanding of the present invention.

As the structural features of the present invention are concerned entirely with the control of the knitted web after it has passed the needles, it is not necessary herein to illustrate or describe the part of the knitting machine particularly concerned in the formation of the web.

An automatic knitting machine of the

type to which this invention is particularly adapted is shown in the re-issue patent to Huse and Huse No. 12,917, above mentioned, and may be referred to for that purpose. In 5 some respects the mechanism illustrated corresponds more closely in its specific form to some of the mechanism shown in the patent to Mayo No. 726,178, granted April 21, 1903, to which reference may also be made for 10 details of the construction unnecessary here to illustrate.

The drawings herein illustrate a specific embodiment of this invention in a somewhat diagrammatic and simplified manner 15 in order that the invention may be clearly and simply disclosed. It is to be understood, however, that the construction even of the preferred form, the arrangement of various elements, their proportion and location 20 are dependent upon the particular type of machine and their structural requirements.

In the drawings:—Figure 1 is a front elevation of so much of a knitting machine as is necessary to understand the invention. 25 Fig. 2 is a top plan view of a stand at the bottom of the machine. Fig. 3 is a view in cross section taken on the line $x-x$ of Fig. 2. Fig. 4 is a left hand side elevation partially in cross section of the machine. Fig. 5 is an 30 enlarged side elevation partially in central vertical cross section of the parts shown in Fig. 6. Fig. 6 is an enlarged front elevation of the cylinder and parts immediately connected therewith. Fig. 7 is a detail in side 35 elevation and partially in vertical cross section of the upper end of the vertical screw and connected parts. Fig. 8 is a top plan view partially in horizontal cross section of the main take-up proper and connected 40 parts.

The machine as shown comprises a suitable framework having the legs 1, the top 2 and the central tie plate 3, and upon this framework are supported for the most part 45 the various instrumentalities, which make up the complete machine.

The usual needle cylinder, carrying the usual cylinder needles, is indicated at 4 and the dial plate carrying the usual dial needles 50 at 5, but the respective sets of needles, their operating instrumentalities and the various other instrumentalities required in the formation of the knitted web are not herein illustrated, as they may be of any familiar 55 and desired type.

The main shaft of the machine is shown at 6, and is provided with fast and loose pulleys 7 and 8 respectively, these pulleys together with a suitable form of belt shifting mechanism being illustrated as showing a means for starting and stopping the knitting machine. As shown the belt shifter 9 is fulcrumed at 10 on a bracket 11 projecting from the frame. A bell-crank lever fulcrumed in the bracket 12, projecting from

the tie plate 3, has one arm 13 connected by a chain 130, running over an idler 131 to the lower end of the belt shifter 9, and its other arm 14 pivoted to the end of a rod 15 extending to the rear of the framework and provided with a transversely projecting end 16, so that when this end 16 is pushed rearwardly the belt will be shifted from the fast pulley 7 to the loose pulley 8 and the knitting machine stopped.

An auxiliary shaft 17 is mounted transversely near the top of the framework in suitable bearings and driven from the main shaft 6 by suitable driving connections as in said Patent No. 726,178, a detailed illustration of which is unnecessary and would only obscure the drawings.

Suitable pattern mechanism herein shown as comprising the barrel 18 provided with cam surfaces and pins carried by a pattern shaft 19 journaled in standards 20 projecting from the tie plate 3, a pattern chain 147, a sprocket wheel 148 loosely mounted on said shaft 19, a pawl 151, and suitable operating mechanism operated from the main 85 shaft and similar in general to corresponding parts in the said Patent No. 726,178 is provided. A detailed illustration or description of the pattern mechanism and the means for operating it may be had by reference to said patent and is unnecessary here.

The knitted web is indicated in outline at 21. It extends from the interior of the cylinder vertically downward and about an idler roll 22 mounted on a stand 23 secured 100 to the floor at the bottom of the machine. It passes from this idler roll about a roll 24 secured to a shaft 25 journaled in brackets 26 carried by the cross piece 27 secured to the two rear legs of the framework and from 105 thence the knitted web passes from the machine.

The roll 24 is roughened on its periphery so as to grip the knitted web and for this purpose may be covered with sand paper or 110 emery cloth. The knitted web is maintained in contact with the periphery of the roll 24 by the weight of a roll 28 mounted in slotted bearings in the brackets 26. The shaft 25 is driven frictionally or yieldingly so as to insure the drawing of the knitted web through the machine, but so as to prevent any more tension than is necessary for that purpose being placed upon the web. As a suitable means for this purpose the shaft 17 is provided with a pulley 29, the shaft 25 with a pulley 30 and a belt 31 connects these pulleys. These elements are so arranged that the belt 31 will slip on one or the other of the pulleys when there is any material 115 amount of peripheral resistance at the roll 24 and thus prevent any undue amount of tension being applied to the knitted web 21. The shaft 25 is also provided with a disk 32 carrying on its periphery one or more freely 120 125 130

pivoted hooks 33. During the ordinary rotation of the shaft 25 the hook 33 will hang in vertical position from its pivot, but if the speed of rotation of the shaft 25 be increased the hook 33 will tend to assume a position radial of the shaft 25 due to centrifugal force and will then come into the path of the end 16 of the belt shifting connections and secure the shifting of the belt from the fast 10 to the loose pulley and the consequent stopping of the knitting machine. This mechanism is provided as a suitable means for stopping the machine if for any reason the formation of the knitted web ceases, as by 15 the breaking of the thread. Should this happen the friction drive 31 at once speeds up the shaft 25 and the machine is stopped.

The main take-up is shown as supported from a carriage 34 having a vertical movement beneath the cylinder. This carriage is provided with a depending sleeve 35 mounted to slide vertically on a vertical screw threaded shaft 36. It is also slotted at its forward edge as indicated at 37 in front of 20 the shaft 36 to slide vertically upon a vertical rod 38.

The screw threaded shaft 36 is journaled at its upper end in a bracket 39, shown as secured to the side of the cylinder 4, and is 25 journaled at its lower end 40 in the stand 23. The screw thread on the shaft terminates short of the top of the shaft, as shown in Fig. 7, and the upper end of the shaft is provided with a bevel gear 41 intermeshing 30 with a bevel gear 42 carried on a shaft 43 journaled at one end in the bracket 39 and in its opposite end in a bracket 44, depending from the top plate 2. The shaft 43 carries at its opposite end a bevel gear 45 intermeshing with a bevel gear 46 carried by the shaft 17. It will thus be seen 40 that the shaft 17 through the connections just described operates to give continuous rotation to the screw threaded shaft 36.

45 The vertical rod 38, upon which the carriage 34 also slides, is loosely secured at its upper end in the bracket 39, and at its lower end in a slot 47 in the stand 23, so that the rod 38 may be moved toward and from the 50 screw threaded shaft 36. A spring 48 attached to the stand 23 acts normally to hold the shaft 38 away from and parallel with the screw threaded shaft 36.

The main take-up carriage is moved downwardly sliding on the shaft 36 and the rod 38 by its own weight and in addition by an adjustable weight 49, shown as secured to a cord or chain 50 passing about an idler roll 51 secured in brackets 52 near the top of 55 the framework, then about an idler roll 53 secured in brackets 54 on the stand 23 and then connected at 54 to the sleeve 35. The main take-up carriage is moved upwardly by means of the screw threaded shaft 60 65 36. For this purpose a pin 55 is mounted

to slide horizontally in the sleeve 35. When the pin 55 is in its inner position toward the shaft 36 it enters between the screw threads in the shaft 36 so that as the shaft 36 revolves the carriage will be slowly raised.

The pin 55 is projected inwardly into engagement with the screw threaded shaft 36 at any position vertically in which the carriage 34 may be by swinging the vertical rod 38 toward the shaft 36. The rod 38 at the 70 required or predetermined time is thus moved by suitable means controlled by the pattern mechanism 18. As herein shown this means comprises a sort of bell-crank lever fulcrumed at 57 on the tie plate 3 having 75 one arm 58 extending in front of the rod 38 and having its other arm 59 coöperating with suitable cam surfaces 60 formed on the side of the barrel 18, shown as the pattern mechanism. It will thus be seen that according to the timing of the pattern mechanism the bell-crank lever is rocked to move the rod 38 and cause the projection of the pin 55 between the screw threads of the shaft 36 and consequently at the required or predetermined time the elevation of the main 80 take-up carriage.

When the take-up carriage reaches its uppermost position it is caught and held and disconnected from the screw threaded 85 portion of the shaft 36 by the outward movement of the pin 55. A suitable form of latch is provided for holding the carriage in its uppermost position. This latch is shown at 61 carried by lever 62. The carriage on its front face is beveled upwardly, as indicated at 63, so that as the carriage moves upwardly this beveled portion will slide over and push back the latch 61, which will then snap beneath the carriage 34 and 90 hold it in its uppermost position. The lever 62 is fulcrumed at 64 on a bracket 66 carried by the framework and extends transversely in front of the rod 38 and is drawn toward the carriage by a suitable spring 65. 100

When the carriage reaches its uppermost position and is caught by the latch 61 the pattern mechanism 18 releases the rod 38 so that it returns to its position parallel with the shaft 36 under the influence of the spring 105 48, and the pin 55 is projected outwardly by the termination of the screw threaded portion of the shaft, leaving the carriage 34 free to slide vertically on the shaft 36 when released by the latch 61.

The latch 61 is released from beneath the carriage 34 to allow it to begin its downward movement at the predetermined and required time by connections to suitable pattern mechanism such as the barrel 18. In 115 125 the particular construction illustrated the free end of the lever 62 rests upon an arm 67 depending from a bracket 68 secured to the front of the cylinder 4. This free end of the lever 62 is curved and located in the 120 130

path of a lever 69 pivoted at 70 to a bracket 71 secured to the top plate. An adjustable rod 72 is pivoted at 73 to the lever 69, and pivoted at its lower end to a lever 74. The lever 74 is pivoted at 90 to a bracket 91 rising from the tie plate 3, and this lever 74 is curved at its lower end and located in the path of a pattern projection 75 suitably mounted on the barrel 18. This projection 10 is so located that at the predetermined and desired time it elevates the rod 72 thus swinging the free end of the lever 69 to the left against the curved free end of the lever 62 thus swinging the lever 62 toward the 15 front of the machine, and withdrawing the latch 61 from beneath the carriage 34.

The main take-up carriage supports and carries the take-up device proper adapted to slide freely over the web when moved upward, but to clamp the web throughout when the downward movement commences. In the construction shown this means comprises a flat upright clamping member 76 adapted to rest upon the rear side of the web 20 and a coöperating clamping member 77 adapted to press the web against the member 76. The clamping member 77 is shown as a dog curved at its upper front edge and pivoted at 78 to an upright 79 supported on 25 the carriage. A spring 80 acts to swing the coöperating edge of the clamping member 77 into contact with the member 76, but allows this edge to move freely downward as the take-up slides up over the web. The 30 two clamping members thus clamp between them the knitted web holding it firmly and securely and in such a manner that the necessary weight may be given the clamp to secure the required degree of tension at the 35 knitting off point, and this is done without any danger of injury to the fabric.

The auxiliary take-up or grab comprises a long rod 81 having at its upper end downwardly inclined projecting teeth 82. This 40 rod is mounted to slide through the bracket 68 and the lower guiding support, such as the tie plate 3, and is given a yielding downward movement through the medium of a spring 83 located between its lower end and the lower support, such as the tie plate 3. The grab is moved upwardly at the same 45 time as the main take-up by means of a lug 84 projecting from the carriage 34 and engaging a vertical adjustable projection 85 on the grab rod 81. The auxiliary take-up 50 serves only to increase or control the tension at some given point on the knitted web and this form of a grab which catches into the web may be used for this purpose without danger of injuring the web, because it 55 is thus employed at only one point and is entirely auxiliary to the main take-up.

The operation of the construction herein 60 illustrated and described as a specific embodiment of the present invention will now

be clear. Assuming that the knitted web is in place extending from the needles about the roller 22 and over the roller 24 and the main take-up and the auxiliary take-up are in their uppermost positions, it will be seen 65 that the grab is arranged with its teeth very close to the knitting point, that the clamping line of the main take-up is well up within the cylinder. The web being drawn down by the slight pull exerted by the roughened 70 surface of the roll 24 and the friction drive 31 will be drawn evenly and steadily, with little tension on the needles in action and will slide freely down past the curved teeth 82 of the grab and between the clamping members 76 and 77 of the main take-up. Assuming also that the machine has completed the knitting of the heel pouch, which 75 in this case is assumed to lie toward the front of the machine, and is just beginning 80 ribbed knitting, the dial needles having come into action, then it is necessary to place more tension upon the web to secure the proper casting off of the stitches from the needles in action during ribbed knitting. 85 The pattern mechanism 18 is so timed as to come into action releasing the latch 61 from beneath the carriage 34. The carriage 34 then drops causing the main take-up members 76 and 77 to clamp the web and the 90 weight of the carriage 34 and its supported parts then hangs upon the web and this weight is increased by the weight supplied at 49 and the carriage 34 thus weighted begins to slide down over the screw 36 and the 95 rod 38. But if this were the only instrumentality applying tension to the web the tension would be unequal around the circular courses of the knitting at the knitting 100 points because of the existence of the heel pouch and imperfect knitting would result. But immediately upon release of the latch 105 61 and the dropping of the carriage 34 the lug 84 is lowered from beneath the projection 85 and the teeth 82 of the grab catch 110 and hang upon this portion of the knitted web and it is moved downward yielding and independently of the main take-up by its spring 83, which is arranged to produce sufficient tension on that side of the 115 web to equalize the tension throughout the web. The action thus continues until the ribbed knitting has progressed to such an extent that the tension exerted by the main take-up will be sufficiently equal throughout 120 the circular course of the knitting at the knitting point when the grab will be stopped as by its head engaging the bracket 68 in its downward movement and the web will continue downwardly under the influence of 125 the main take-up again sliding over the teeth 82 of the grab.

The pattern mechanism is so arranged as to cause the main take-up to clamp and the auxiliary take-up to catch the web at a 130

point beyond or above the completion of the ribbed knitted portion of the previous stocking so that no undue tension is placed upon that portion of the web where the dial needles have dropped out of action, and consequent raveling is impossible.

When the ribbed knitting ceases and the machine changes to plain circular or reciprocating knitting, the pattern mechanism is timed again to come into action and, through the bell-crank levers 58 and 59, to move the rod 38 toward the screw 36 thus projecting the pin 55 between the screw threads of the screw 36. When the carriage 34 reaches its uppermost position the bevelled recess 63 slides over the latch 61, the pin 55 is withdrawn and the carriage is caught by the latch 61 in its uppermost position, ready, under the control of the pattern mechanism, again to clamp the web, the auxiliary take-up at the same time being raised into uppermost position by the lug 84. Thus the web is free from the additional tension caused by the main take-up device upon the completion of the ribbed knitting, so that again no undue strain is placed upon the portion of the web where the dial needles have dropped out of action and raveling is impossible. During the knitting of the ensuing portion of the stocking and until ribbed knitting is again to begin, the web is taken up simply by the roll 24 and its friction drive.

Having fully described my invention, what I claim as new and desire to secure by Letters Patent is:—

1. In a circular knitting machine, the combination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, and pattern controlled means for elevating the take-up and releasing it to clamp the web.

2. In a circular knitting machine, the combination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, pattern controlled means for elevating the take-up and releasing it to clamp the web, and means connected to said take-up and acting therethrough to place tension on the web during the downward movement of the take-up.

3. In a circular knitting machine, the combination with operating means for the needles, of pattern mechanism for controlling the operation of said needles to produce

either ribbed, plain circular or reciprocating work as desired, a take-up for the fabric being knit adapted to slide over the web when moved upwardly and to clamp the web when moved downwardly, pattern controlled means for elevating the take-up and releasing it to clamp the web, and an auxiliary take-up device mounted to slide at one side of the web and to catch in one side of the web upon its said downward movement.

4. In a circular knitting machine, the combination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, pattern controlled means for elevating the take-up and releasing it to clamp the web, an auxiliary take-up device mounted to slide at one side of the web and to catch in one side of the web upon its said downward movement, and yielding means for causing the downward movement of the auxiliary take-up device and means for securing its upward movement from the take-up.

5. In a circular knitting machine, the combination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, elevating means for said take-up, pattern controlled means to effect the engagement of the take-up and the elevating means and secure the elevation of the take-up and to release the take-up from the elevating means at a predetermined time allowing the take-up to clamp and hang upon the web.

6. In a circular knitting machine, the combination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, elevating means for said take-up, pattern controlled means to effect the engagement of the take-up and the elevating means and secure the elevation of the take-up and to release the take-up from the elevating means at a predetermined time allowing the take-up to clamp and hang upon the web, a grab mounted to slide at one side of the web and to catch the web upon its downward movement, and means for securing the elevation of the grab from the take-up.

7. In a circular knitting machine, the com-

bination with operating means for the needles, of pattern mechanism for controlling the operation of said needles to produce either ribbed, plain circular or reciprocating work as desired, a take-up for the fabric being knit adapted to slide over the web when moved upwardly and to clamp the web when moved downwardly, elevating means for said take-up, pattern controlled means to 10 effect the engagement of the take-up and the elevating means and secure the elevation of the take-up and to release the take-up from the elevating means at a predetermined time allowing the take-up to clamp and hang upwardly on the web, a grab device mounted to slide at one side of the web and to catch the web upon its downward movement, a spring connected to the grab and acting to move the same down yieldingly, the take-up acting 15 upon its upward movement to raise and hold the grab in its elevated position and acting when released to release the grab to downward movement.

8. In a circular knitting machine the combination with operating means for the needles, of mechanism for controlling the operation of said needles to produce either ribbed or plain circular work as desired, a take-up for the fabric being knit adapted to 20 slide over the web when moved upwardly and to clamp the web when moved downwardly, means to cause the take-up to clamp the web at a point above a change from ribbed to plain work upon or about the time 25 of the commencement of the knitting of a succeeding section of ribbed work.

9. In a circular knitting machine the combination with operating means for the needles to produce either ribbed or plain circular work as desired, of a vertical screw 30 threaded shaft and means for rotating it, a carriage mounted to slide parallel to said shaft, a take-up comprising web-clamping jaws mounted on said carriage and means 35 automatically actuated to connect the said carriage to the said shaft and cause the upward movement of the carriage.

10. In a circular knitting machine the combination with operating means for the needles to produce either ribbed or plain circular work as desired, of a vertical screw 40 threaded shaft and means for rotating it, a carriage mounted to slide parallel to said shaft, a take-up comprising web-clamping

jaws mounted on said carriage and means 55 automatically actuated to connect the said carriage to the said shaft and cause the upward movement of the carriage, a latch to catch and retain the carriage in elevated position and means automatically actuated to 60 release the latch and allow the take-up and carriage to clamp and hang upon the web.

11. In a circular knitting machine the combination of a needle cylinder, a two part take-up for the fabric being knit adapted 65 to slide over the web when moved upwardly and to clamp the web between its parts when moved downwardly, and means for elevating the take-up and causing it to clamp the web at a point well up in the cylinder. 70

12. In a circular knitting machine the combination with operating means for the needles, of pattern mechanism for controlling the operation of said needles to produce either ribbed or plain work as desired, a 75 take-up for the fabric being knit adapted to slide over the web when moved upwardly and to clamp the web when moved downwardly, and means for elevating the take-up and causing it to clamp the web upon a plain 80 knitted portion after a change has been effected from the knitting of said plain portion to the knitting of a consecutive ribbed portion.

13. In a circular knitting machine the combination with operating means for the needles, of pattern mechanism for controlling the operation of said needles to produce either ribbed or plain work as desired, a take-up for the fabric being knit adapted to 85 slide over the web when moved upwardly and to clamp the web when moved downwardly, and means for elevating the take-up and causing it to clamp the web upon a plain knitted portion after a change has been effected from the knitting of said plain portion to the knitting of a consecutive ribbed portion, an auxiliary take-up device mounted to slide at one side of the web and 90 to catch in one side of the said plain knitted portion upon its downward movement. 95

In testimony whereof, I have signed my name to this specification, in the presence of two subscribing witnesses.
